UNITED STATES PATENT OFFICE.

JOHN H. PARSONS, OF FERNDALE, MICHIGAN.

GASOLINE-RESERVE-SUPPLY APPARATUS.

Original application filed October 24, 1921, Serial No. 510,137. Divided and this application filed September 27, 1922. Serial No. 520,774.

This invention relates to gasoline reserve supply apparatus for automobiles, motor boats, and the like and has for its primary object the reservation within the usual gasoline line supply tank of all the gasoline below a predetermined level as a reserve supply, with provisions whereby an alarm will be given when such level of the gasoline in the tank is reached, after which the reserve supply can be utilized in driving the automobile to a filling station.

Another object of this invention is to arrange the suction pipe leading from the gasoline tank to the carburetor so that gasoline is at all times drawn off from the bottom of the tank, thereby preventing the accumulation of water or fuel of low gravity at the bottom of the tank to render the reserve supply of inferior quality to the main supply of gasoline.

A further object of my invention is the provision of simple and comparatively inexpensive means for preventing the consumption of the full supply of fuel by the engine without first requiring the driver to operate the mechanism to permit the use of the reserve supply and thereby calling his attention to the fact that it is necessary to obtain a fresh supply of gasoline, such mechanism being readily operated by the driver without leaving his seat and comprising the closing of an air-filled bypass pipe to permit the resumption of fuel feeding through the same supply pipe.

The above and other objects of my invention will be apparent from the following description wherein reference is made to the accompanying drawings illustrating preferred embodiments of my invention, and wherein similar reference numerals designate similar parts throughout the several views.

In the drawings:

Fig. 1 is a diagrammatic view, with parts in section, showing my reserve supply apparatus arranged so that the reserve supply can be brought into use by turning a valve mounted on the dashboard of an automobile.

Fig. 2 is a side elevation of such valve with the dashboard shown in section, and

Fig. 3 is a detail front view of the dashboard and valve.

This application is a division of my application filed October 24, 1921, Serial No. 510,137, now Patent No. 1,461,805, and re-

lates particularly to an embodiment disclosed but not claimed in such parent application.

The claimed disclosure herein utilizes a feed pipe 11^c divided longitudinally into compartments, through one of which, as for example that shown on the right side in Fig. 1, liquid gasoline is drawn into the pipe line 8^c secured at its rear extremity upon a T shaped valve casing 7^c and leading to a valve casing 29 mounted upon the dashboard 30 of an automobile and thence to the vacuum tank or carburetor of the automobile in the usual manner. The valve casing 29 is herein illustrated as substantially T shaped with three passageways radiating from the central portion. The pipe line 8^c is preferably connected with the central passageway 31 and the pipe line 8^d leading to the vacuum tank or carburetor with the passageway 32 at the right side of the valve casing 29. A port 14^c is positioned in the opposite compartment of the feed pipe 11^c at any desired height above the bottom of the tank 5^c and an upper port 15^c connects this compartment with the bypass pipe 33 connecting the left hand portions of the T shaped valve casings 7^c and 29.

The valve 34 is suitably seated in the casing 29 and provided with three radial passageways 31, 32 and 33 when in the position shown in Fig. 1. This position is the one maintained when the main supply of gasoline is being drawn from the tank 5^c. In operation the liquid gasoline is drawn upwardly from adjacent the bottom of the tank 5^c through the right hand compartment of the feed pipe 11^c into the pipe line 8^c, passageways 31 and 32 of the valve casing 29, into the continuation 8^d of the pipe line leading to the vacuum tank or carburetor. This action continues until the liquid level falls below the port 14^c in the opposite compartment of the feed pipe 11^c, whereupon air is drawn through such compartment into the bypass pipe 33 and the passageway 32 of the valve casing 29, breaking the vacuum and thereby stopping the flow of the liquid gasoline. The engine will thereupon give warning, as hereinbefore described, that the fuel supply is low. The valve 34 can then be rotated by grasping the knob 35 thereof and turning it through a quarter revolution, thereby moving the radial pas-

age of the valve 34 opening into the bypass 33, as shown in Fig. 1, into position to open into the central passageway 31 of the valve casing 29, and simultaneously swinging 5 the passage formerly opening into the central passage 31 into position to register with the right hand passageway 32. The left hand passageway 33 is closed by this movement of the valve 34, thereby preventing 10 the entrance of air to the pipe line 8^a to further prevent the formation of a vacuum to draw up liquid fuel.

In Fig. 3, I have illustrated a dial adapted 15 to be mounted on the dashboard 30 with a pointer 36 mounted on the stem of the valve 34 to show whether the main or reserve supply of gasoline is being drawn upon.

While it will be apparent that the illustrated embodiments of my invention herein disclosed are well calculated to adequately fulfill the objects and advantages primarily stated, it is to be understood that the invention 20 is susceptible to variation, modification and change within the spirit and scope of the subjoined claims.

Having described my invention, I claim—

1. In a device of the character described, a tank adapted to contain liquid fuel, a feed 20 pipe mounted therein and extending from adjacent the bottom of the tank to a position above the tank, said feed pipe being divided longitudinally into compartments, a valve casing mounted on the vehicle in a 25 position convenient to the driver's seat, a pipe line leading from one compartment to the valve casing, a bypass pipe leading from the other compartment to the valve 35 casing, a pipe connecting the valve casing to the carburetor of the engine, and an apertured valve mounted in said casing and movable to positions connecting the bypass pipe with or closing it off from said 40 pipe between the valve casing and carburetor.

2. In a device of the character described, a tank adapted to contain fuel, a feed pipe

mounted therein and extending from adjacent the bottom of the tank to a position above the tank, said feed pipe being longitudinally divided into compartments, said compartments having upper ports exterior of the tank and one of said compartments also having a lower port therein spaced a predetermined distance from the bottom of the tank, a pipe line connecting the other compartment with the carburetor of the engine, a valve casing adapted to be mounted on the dash-board of a vehicle arranged intermediate the ends of said pipe line, a bypass pipe connecting the compartment having upper and lower ports with said valve casing, and a valve in said casing with passageways therein arranged when in one position to connect said bypass pipe with said pipe line, and rotatable to a position closing said bypass pipe.

3. In a device of the character described, a tank adapted to contain fuel, a feed pipe mounted therein and extending from adjacent the bottom of the tank to a position above the tank, said feed pipe being longitudinally divided into compartments, said compartments having upper ports exterior of the tank and one of said compartments also having a lower port therein spaced a predetermined distance from the bottom of the tank, a pipe line connecting the other compartment with the carburetor of the engine, a valve casing adapted to be mounted on the dash-board of a vehicle arranged intermediate the ends of said pipe line, a bypass pipe connecting the compartment having upper and lower ports with said valve casing, a valve in said casing with passageways therein arranged when in one position to connect said bypass pipe with said pipe line, and rotatable to a position closing said bypass pipe, and indicating means on said valve for visually indicating in which position the passageways of the valve are placed.

JOHN H. PARSONS.
